UNITED STATES PATENT OFFICE.

CYRUS T. SCHIRMER, OF NEWTON, MASSACHUSETTS, ASSIGNOR TO THE HOLTZER-CABOT ELECTRIC COMPANY, OF ROXBURY, MASSACHUSETTS, A CORPORATION OF MASSACHUSETTS.

ELECTRIC SIGNAL.

Application filed January 5, 1922. Serial No. 527,177.

To all whom it may concern:

Be it known that I, CYRUS T. SCHIRMER, a citizen of the United States, residing at Newton, in the county of Middlesex and 5 State of Massachusetts, have invented certain new and useful Improvements in Electric Signals; and I do hereby declare the following to be a full, clear, and exact description of the invention, such as will enable others skilled in the art to which it 10 pertains to make and use the same.

The present invention relates to an improvement in electric signals.

The object of the invention is to produce a 15 construction which, while adapted to make an audible signal by the use of a direct current, is also adapted for use with alternating current, to which it is more especially adapted.

20 In electric signals used with alternating current there is a liability, owing to the alternations of the current, to chattering of the moving signal giving element, and one of the objects of this invention is to overcome this chattering. Another object of 25 the invention is to reorganize and improve, as well as to simplify and reduce the cost of electric signals.

The accompanying drawing illustrates an 30 elevation of the preferred form of the device.

The preferred form of the invention is described as follows: The device is applied with a base 10, to which an electro-magnet 35 11 is secured. The pole piece 12 of the magnet is projected beyond the end of the spool, and is cut away at 13 for the purpose of localizing the lines of force of the magnet. A non-magnetic metal stop 14 is provided, 40 which is secured by a screw to the end of the pole piece 12. A tapper 15, pivoted at 16, is normally held in raised position by a spring 17. The tapper 15 is made of soft iron, and the stop 14 is so located that the 45 tapper is above the end of the pole piece in its normal or unenergized condition. When current is sent through the electro-magnet coil 11, it energizes the pole piece 12, which attracts the tapper to it. The tapper is 50 made heavy enough either by its own bulk

or by an additional weight 18 secured to it, so that the momentum which it acquires in moving toward the end of the pole piece is sufficient to carry it by that pole piece far enough so that the non-magnetic button 19 55 on the lower surface of the end of the tapper strikes the flat surface 20 of the pole piece, making an audible blow. So long as the coil 11 is energized, the tapper will then be held opposite the end 21 of the pole piece, 60 but when it is de-energized by opening the circuit, the spring 17 will again restore the tapper to its original position. To the base 10 is secured a piece of vulcanized fiber 22 by means of the screws 23. To this are secured the terminal connectors 24 and 25, to which the ends of the wire of the coil 11 are soldered. The connectors 24 are secured to the vulcanized fiber block by screws 26, and the leading in wires are secured to the connectors 24 by the screws 27.

The gist of the invention consists in arranging the tapper so that the attraction of the magnetic field created in the pole piece will set it in motion, and cause it to move 75 not only to the point of greatest attraction, but by its momentum carry it beyond that point, so that it will strike a blow upon a part adapted to receive it. Thus any chattering of the tapper due to the reversals of 80 current in the coil, if an alternating current is used, will be avoided.

Having thus described the invention, what is claimed is:

An electric signal having, in combination, 85 a base, an electro-magnet provided with a spool and mounted on the base having a pole piece projected beyond the end of the spool and cut away to laterally localize the lines of force of the magnet, a non-magnetic stop 90 secured to the end of the pole piece, a pivoted tapper, a spring normally holding the tapper in raised position against the stop above the end of the pole piece, said tapper being provided with a non-magnetic button 95 adapted when the magnet is energized to strike a portion of the pole piece to make an audible blow.

CYRUS T. SCHIRMER.
